[57] **CLAIM**

The ornamental design for a digital multimeter for electrical measurement, as shown and described.

DESCRIPTION

FIG. 1 is a front elevational view of a digital multimeter for electrical measurement showing my new design;

FIG. 2 is a left side elevational view thereof;

FIG. 3 is a bottom plan view thereof;

FIG. 4 is a top plan view thereof;

FIG. 5 is a right side elevational view thereof;

FIG. 6 is a rear elevational view thereof.
